UNITED STATES PATENT OFFICE.

OSCAR A. DANIELSON, OF NEW YORK, N. Y., ASSIGNOR TO WESTERN ELECTRIC COMPANY, OF NEW YORK, N. Y., A CORPORATION OF ILLINOIS.

SELECTING APPARATUS.

1,086,899.

Specification of Letters Patent. Patented Feb. 10, 1914.

Application filed April 10, 1913. Serial No. 760,232.

To all whom it may concern:

Be it known that I, OSCAR A. DANIELSON, a citizen of the United States, residing at New York, in the county and State of New 5 York, have invented a certain new and useful Improvement in Selecting Apparatus, of which the following is a full, clear, concise, and exact description.

This invention relates to electrical selecting apparatus and is particularly adapted for use in printing telegraph receivers although not exclusively limited to such use.

This invention is disclosed but not claimed in a copending application of Arthur H. 15 Adams and Amos F. Dixon, Serial No. 737,851 filed December 20, 1912 and assigned to my assignee.

The object of this invention is to provide an electrical selecting apparatus of the above 20 type which is capable of furnishing the required circuit connections by the use of a small number of relays.

To the above end a plurality of polarized relays is provided, so arranged in the main 25 line conductors and so interconnected in a novel manner, that secondary circuits may be selected upon the receipt of a combination of impulses from a distant transmitting station.

30 This invention will be fully understood from the following description taken in connection with the accompanying drawing in which the selecting apparatus is shown diagrammatically.

35 The current impulse-transmitting apparatus at a distant station may be of any suitable form as, for example, keys 10, 20, 30 and 40 which control the application of current from two grounded sources of energy 40 50 and 51. By the proper manipulation of these current control keys, the desired combination of positive and negative impulses may be transmitted over the main line conductors L' and L^2 which provide connec-

45 tions between the transmitting apparatus at a distant station and the selecting apparatus at a receiving station. These conductors are preferably grounded through polarized relays 55, 56, 57 and 58. The polarized re-

50 lays 55, 56, 57 and 58 may be polarized in any manner, but it has been found convenient to furnish each relay with a second winding through which current from a grounded source of energy 60 normally flows. This polarizing circuit may be traced

from grounded battery 60, conductor 62, lower winding of relay 56, conductor 63, lower winding of relay 58, conductor 64, lower winding of relay 55, conductor 65, lower winding of relay 57 to ground 60 and back to battery. Two of the relays, one in each main line conductor, are wound so as to be operative on positive current only, and the other relay in each main line conductor is wound to be responsive to negative currents only. In the selecting apparatus shown, relays 55 and 57 are polarized to respond to positive currents only and relays 56 and 58 to respond to negative currents only. The polarized relays 55, 56, 57 65 and 58 control the selection of secondary circuits 70, 80, 90, 100, 110 and 120 in which are located secondary relays 130, 140, 150, 160, 170 and 180. The secondary relays may control the connection to circuits 192, 194, 196, 198, 200 and 204 and in each of the 70 circuits 191 to 204 inclusive may be connected groups of type magnets to form a plurality of type selecting branches. However, the particular arrangement of apparatus in the secondary circuits is immaterial 75 to the operation of the system of this invention.

A sufficient description of the details of the circuit will appear from the following 80 description of the operation of receiving a particular combination of impulses over the main line conductors L' and L^2 . Let it be assumed that a selection is desired requiring the combination of a negative impulse over 85 line conductors L' and L^2 simultaneously followed, after an interval of no current, by a positive impulse over line conductor L' . A negative impulse arriving simultaneously over line conductors L' and L^2 passes 90 through the polarized relays 55, 56, 57 and 58 to ground, causing only the negatively polarized relays 56 and 58 to attract their armatures. The attraction of the armatures of relays 56 and 58 closes a ground 95 connection for the secondary circuit 110 containing the relay 170, through the lower armature of relay 56 and the armature of relay 58. At the cessation of the first impulse, the polarized relays return to normal 100 in condition to receive a second impulse. The second impulse passes through both relays 55 and 56, the former being the only one energized. A ground is thereby provided 105 for the secondary circuit 70 containing the 110

relay 130, through the armature of relay 55 and the upper armature of relay 57.

What I claim is:

In a selecting apparatus the combination 5 of a pair of main line conductors, two polarized relays in each main line conductor, said relays being connected in parallel, six secondary circuits, and circuit connections whereby said polarized relays may complete

any of said secondary circuits upon the receipt of current impulses from said main line conductors.

In witness whereof, I hereunto subscribe my name this 7th day of April A. D. 1913.

OSCAR A. DANIELSON.
